UNITED STATES PATENT OFFICE.

CHARLES SEESSLE, OF NEW YORK, N. Y., ASSIGNOR TO THE NEW YORK AUTOMATIC SCALE COMPANY, OF SAME PLACE.

STOP-MOTION FOR GRAIN-WEIGHING APPARATUS.

SPECIFICATION forming part of Letters Patent No. 332,116, dated December 8, 1885.

Application filed June 26, 1885. Serial No. 109,803. (No model.)

To all whom it may concern:

Be it known that I, CHARLES SEESSLE, of the city, county, and State of New York, have invented certain new and useful Improvements 5 in Stop-Motions for Grain-Weighing Apparatus, of which the following is a specification:

This invention relates to an improved stop-motion for automatic grain-weighing machines, and more especially to the grain-weighing machine for which Letters Patent have been granted to me heretofore under date of May 5, 1885, No. 317,220, so that the machine is brought automatically to a stop after a determined quantity of grain has been weighed; 15 and the invention consists of a stop-motion for automatic grain-weighing machines, in which the scale-beam of the machine is connected by suitable transmitting mechanism with an intermittently-rotating cylinder having a longitudinal tooth and a shaft that is threaded on the outer end, the tooth engaging a gear-wheel of a second cylinder sliding on a fixed rod, said second cylinder being engaged by the forked end of a laterally-traversing screw-arm 20 that is moved forward by the threaded end of the shaft of the first cylinder. The lower cylinder is provided with numerals arranged in a spiral line on the surface of the same, and provided with a nose at the opposite end, 25 which nose engages a laterally-guided and spring-cushioned pusher-rod that operates a fulcrumed lever-rod which releases a drop-lever having pawls at the side of the hopper of the weighing-machine, said pawls engaging a stop on an upwardly-extending arm of the oscillating supply-valve, so as to interrupt the operation of said valve and hold it in horizontal position when the machine has weighed the required quantity of grain.

40 In the accompanying drawings, Figure 1 represents a side elevation of a grain-weighing machine with my improved stop-motion, showing its connection with the scale-beam and supply-valve of the machine. Fig. 2 is a side elevation of the registering mechanism of the stop-motion drawn on a larger scale, and Fig. 3 an end view of Fig. 2. Fig. 4 is an end elevation of the grain-weighing machine and stop-motion. Fig. 5 is a vertical

transverse section of the register of the stop-motion on line x x , Fig. 6, including the face-plate and cross-section of the pusher-rod and stop-valve. Fig. 6 is an elevation of the register of the stop-motion drawn on a larger scale, and with parts broken off. Fig. 7 is a detail side view of the gear for operating the registering-cylinders of the stop-motion.

Similar letters of reference indicate corresponding parts.

In the drawings, A represents a scale-beam 6c of a grain-weighing machine, which beam is arranged with an extension-arm, a, that is connected by a pivot-rod, b, with an oscillating arm, d, (see Fig. 3,) having at its opposite end a weighted pawl, d'. The oscillating arm 65 d turns loosely on the end of a horizontal shaft, B', which is supported in bearings of a casing, C, within which the registering mechanism of the stop-motion and the counter of the weighing-machine are arranged. The 7c weighted pawl d' engages a ratchet-wheel, d², that is keyed to the shaft B'. A second shorter connecting-rod, d³, connects the arm d with a second oscillating arm, d⁴, having a spring-pawl, d⁵, which latter engages the teeth of a 75 ratchet-wheel, d⁶, on the shaft C' of the counter C', which is of any approved construction, and located at the upper part of the casing C, as shown in Figs. 1, 2, and 3.

When the weighted end of the scale-beam 8c A is raised by the weight of the grain in the bucket, the connecting-rods b and d³ and the arms d and d⁴ operate the pawls d' and d⁵ and turn the ratchet-wheels d² d⁶ for the distance of one tooth. When the bucket is discharged, 85 the weighted end of the scale-beam descends, while the extension-arm is raised, so that the pawls d' d⁵ are lifted and moved forward into engagement with the next adjoining teeth of the ratchets d² d⁶, into position to be turned by 9c the next motion of the scale-beam, as described.

To the shaft B' is keyed a cylinder, B, which receives intermittent rotating motion by the scale-beam and intermediate pawl-and-ratchet mechanism. The shaft B' is made of double 95 the length of the cylinder B and screw-threaded at that end not covered by said cylinder. The shaft B' is extended through the casing C

and provided with a hand-crank, B², for turning the same from the outside. The cylinder B has at the inner end, next to the threaded part of the shaft B', the numerals 0 to 9 arranged on its circumference, of which one at a time is visible through a front opening of the casing C. The cylinder B engages by a longitudinal tooth, e, a gear-wheel, e', with ten notches, as shown in Fig. 6, that is attached 5 to the end of a second cylinder, D, that is arranged below the cylinder B and made equal in length therewith. The cylinder D is placed loosely on a shaft, D', that is firmly secured to the casing C. The numbers from 1 to 1000 10 are arranged in a spiral line on the perimeter of the cylinder D, which is turned for the distance of one tooth when the cylinder B has completed one entire rotation. At the opposite end of the cylinder D is arranged a fixed 15 nose, f, and adjoining to the nose f a grooved collar, f', is attached to the cylinder D, which is engaged by the fork-shaped end of a traversing-arm, f², the opposite end of which is made in the shape of a nut, f³, that is caused to 20 move on the threaded end of the shaft B' by the turning of the same. The forked arm f² moves thereby the cylinder D forward on its supporting-shaft D' until the arm f² arrives 25 at the shoulder f⁴ on the opposite side wall of the casing C. The longitudinal tooth e of the cylinder B is kept in mesh with the gear-wheel e' throughout the traversing motion of the cylinder D. The numbers on the cylinder D are visible successively through a second 30 opening in the front wall of the casing C, said second opening being vertically below the opening for the numerals on the cylinder B, as shown in Fig. 2.

When it is desired that the grain-weighing 35 machine is to weigh a determined quantity of grain, the cylinders B and D are first adjusted to the number required by turning the shaft B' by the hand-crank in an opposite direction to the motion imparted to the same by the 40 transmitting mechanism until the required number appears in the openings of the inclosing-casing. The successive weighing of grain 45 by the machine turns the cylinder B and moves the cylinder D from the right toward the left until it arrives at zero, and is stopped 50 by contact with the opposite side wall of the casing C. When the zero-figure of the cylinder D appears in the front opening of the casing, the nose f engages the rounded-off 55 head of a sliding and spring-cushioned pusher-rod, g, which is clamped at its outer end to a stop-sleeve, g', that is pivoted to one end of a fulcrumed lever, F, the opposite end of which engages a drop-lever, F', that is pivoted 60 at its rear end to the side wall of the hopper of the grain-weighing machine, and provided at its front end with a handle for setting the drop-lever. When the lever F is actuated by the nose f, the outer end of the 65 same clears the drop-lever F' and permits the

latter to drop. The drop-lever is provided with two stop-pawls, h h, that engage a central stop, h', of an upwardly-extending arm, H', of the oscillating supply-valve H of the grain-weighing machine as soon as the drop-lever is released from the lever F. As soon as the pawls h of the drop-lever F engage the central stop, h', of the upwardly-extending arm H' of the supply-valve H the latter is held in horizontal position, and thereby the action of the 70 grain-weighing machine interrupted. This takes place in a reliable and automatic manner whenever the required quantity has been passed through the weighing-machine, so that the same is adapted for weighing of determined quantities of grain, as required in breweries, distilleries, and for other purposes. 75 Having thus described my invention, I claim as new and desire to secure by Letters Patent—

1. The combination, with a scale-beam and 80 suitable transmitting mechanism, of a stop-register consisting of an axially-turning cylinder and intermittently-rotating and laterally-sliding cylinder, said cylinder having a 85 projecting nose, a guided and spring-cushioned 90 pusher-rod actuated by said nose, a supply-valve, and a lever mechanism actuated by the pusher-rod for stopping said supply-valve and arresting the motion of the weighing apparatus, substantially as set forth. 95

2. The combination, in a grain-weighing machine, of a scale-beam, transmitting mechanism, a stop-register consisting of an intermittently-rotating cylinder keyed to a threaded shaft, a second intermittently-rotating and laterally-sliding cylinder having numerals 100 arranged in a spiral on its perimeter, a fixed guide-shaft for said cylinder, a laterally-traversing arm operated by the threaded shaft and engaging the laterally-sliding cylinder, a 105 projecting nose at one end of the cylinder, a guided and spring-cushioned pusher-rod, a fulcrumed lever, a drop-lever having stop-pawls, a supply-valve, and an arm keyed to the supply-valve of the weighing-machine, 110 said arm having a central stop-tooth for the pawls, substantially as set forth. 115

3. The combination, in a stop-motion for grain-weighing machines, of an intermittently-rotating shaft threaded at one end, a cylinder keyed to said shaft, a grooved collar fixed to said cylinder and having a longitudinal tooth, a second cylinder having a gear-wheel meshing with the tooth and sliding on a fixed guide-shaft, and a laterally-traversing arm having a forked end and engaging a grooved collar of the sliding cylinder, substantially as set forth. 120

4. The combination of a transmitting pawl-and-ratchet mechanism operated by the scale-beam of a grain-weighing machine, an intermittently-rotating shaft, being threaded at one end, and having a handle at the outer end, a cylinder keyed to the smooth end of said shaft and having a longitudinal tooth, a sec- 125 130

ond cylinder having a gear-wheel meshing with said tooth, and a grooved collar, a fixed shaft for guiding said cylinder, and a laterally-traversing arm moving by a screw-nut on the threaded shaft, and having a forked end for engaging the collar of the traversing-cylinder, substantially as set forth.

In testimony that I claim the foregoing as my invention I have signed my name in presence of two subscribing witnesses.

CH. SEESSLE.
